UNITED STATES PATENT OFFICE.

CHARLES M. JOHNSON, OF PARIS, MAINE.

DESIGN FOR A CHECK-HOOK.

SPECIFICATION forming part of Design No. 32,061, dated January 2, 1900.

Application filed December 1, 1899. Serial No. 738,930. Term of patent 7 years.

To all whom it may concern:

Be it known that I, CHARLES M. JOHNSON, a citizen of the United States, residing at South Paris, in the county of Oxford and State of Maine, have invented and produced a new and original Design for Check-Hooks; and I do hereby declare the following to be a full, clear, and exact description of the same, reference being had to the accompanying drawings, forming a part thereof.

Figure 1 is a perspective view of a check-hook embodying my design for the same, and Fig. 2 is a rear view thereof.

The leading feature of my design consists of an attaching portion comprising an upper and lower member, with a space between them, an upwardly-extending ring, and an upwardly-extending projection or arm to receive and retain the bridle-rein.

In the accompanying drawings, A represents the body portion of the check-hook, which is formed with an upper portion *a*, the lower portion *c*, and the connecting portion *d* at its forward end, the portions *a* and *c* be-

ing disconnected at their rear ends, as at *e*. 25 The upper portion *a* is formed at or near its forward end with an upwardly-extending ring portion and at its rear end with an upwardly and slightly-rearwardly extending curved arm *f*, the inner periphery of the ring at its 30 upper portion being on a plane below the highest point of the upwardly-extending arm *f*. The portions *a* and *c* are each provided with a vertically-arranged bolt-aperture *a'* and *c'*, respectively, which apertures register with each 35 other.

Having now described my invention, what I claim as new, and desire to secure by Letters Patent of the United States, is—

The design for a check-hook, substantially 40 as herein shown and described.

In testimony whereof I hereunto affix my signature in presence of two witnesses.

CHARLES M. JOHNSON.
